[57] **CLAIM**

The ornamental design for a pastry sheet or the like, substantially as shown and described.

DESCRIPTION

FIG. 1 is a top plan view of a pastry sheet or the like showing our new design;

FIG. 2 is a side elevational view thereof; and

FIG. 3 is another side elevational view thereof. The bottom surface is substantially plain and unornamented.

FIG. 1

FIG. 2

FIG. 3
